UNITED STATES PATENT OFFICE

HERMANN M. HESSENBRUCH, OF WYNNEWOOD, PENNSYLVANIA, ASSIGNOR TO PHILADELPHIA LAWN MOWER COMPANY, INC., OF PHILADELPHIA, PENNSYLVANIA, A CORPORATION OF PENNSYLVANIA

ADJUSTMENT MEANS FOR PIVOTED ELEMENTS

Application filed November 23, 1929. Serial No. 409,221.

This invention relates to means for effecting adjustments of pivoted elements such, for example, as the rockably-mounted stationary knives of lawn mowers; said knives being 5 adapted for angular movement toward, or away from, the rotary cutting-reel.

More particularly the present improvements have reference to a type of means including freely guided adjuster-screws with 10 co-active means serving to restrain said screws against axial displacement.

The general object of my invention is to furnish a means, of the type referred to in the preceding paragraph, which is more particularly, although not essentially, adapted to lawn mowers having sheet metal side plates or frames.

With the just recited and other objects in view, this invention may be said to comprise 20 the means illustrated in the accompanying drawings, hereinafter described and particularly set forth in the appended claims, together with such variations and other applications thereof as will suggest themselves to 25 those skilled in the art to which said invention appertains.

In the drawings:

Fig. I is a broken and in part sectional view 30 of portions of a lawn mower illustrating the application of my novel adjustment means to the stationary knife thereof.

Fig. II is a top plan view of the same.

Fig. III is a sectional view, taken as indicated by the arrows III—III in Fig. I; and,

Fig. IV is a perspective view of a nut or locking element hereinafter further explained.

Referring more in detail to the drawings, the reference numeral 5 designates a broken 40 portion of one of the usual side plates of a lawn mower, 6 a similar fragmentary part of the rotary cutting-reel, 7 the shaft thereof; and 8, one of the spiral blades composing a part of the aforesaid cutting-reel: all of said 45 parts, with the exception of the side plate 5, not entering into the present improvements other than as subsidiary features.

As best appreciated from Figs. I—III, inclusive, the side plate 5 is conveniently of sheet-metal, while the stationary knife blade

9 is removably secured by one or more screws 10, to a "back" 11, having an apertured rocker 12 at each end, for engagement by the screw-threaded shank of a stud 13, afforded pivotal bearing at 14, in a downwardly directed lug 15 of the side plate 5.

Adjustment of the stationary knife 9 in an upward or downward direction, relative to the spiral blade 8 of the rotary cutting-reel 6, is controlled by means of vertically-disposed longitudinally-movable adjuster-screws 16 which have "free" guidance in abutment loops 17 pressed, extruded or otherwise formed, out of the side plate 5. These loops or abutments 17 are preferably located on the inner face of the side plate 5, and they are of a size to semi-disengagingly embrace the adjuster screws 16.

Beneath the loops or abutments 17, each adjuster-screw 16 is provided with a threadedly-engaging nut or locking element 18, while said screws are cross-cut at 19 for application of an ordinary screw-driver. Particular attention is here directed to the locking elements or nuts 18 which are conveniently, although not essentially, of the rectangular variety; each said nut being "formed" to provide a flat side or eccentric face 20—Figs. III and IV—in close proximity to the threaded bore 21. This flat side or face 20 on each nut 18, it is to be remarked, is designed to abut the inner surface of the side plate 5 below a loop or abutment 17, so as to position the associated adjuster-screw 16 in vertical position, or axially parallel with the side plate 5, as best seen in Fig. III; while likewise serving to effectively restrain such nuts against rotation.

The lower ends of the adjuster-screw 16 engage the flanking ledge portions 22 of the rocker 12, to thereby limit movement of the stationary knife blade 9; and it will be apparent that, when one of said screws is driven down, the nut 18 thereon will be "jammed" against the under face of the associated abutment loop 17 in a manner that locks the blade 9 at the requisite adjustment relative to the spiral blade 8, when the other adjuster-screw 16 is opposingly driven. It will thus be understood that when both adjuster screws are

driven "home" tightly, the stationary knife is rigidly and securely locked at whatever adjustment it is desired to be "set"; also that the eccentric faces 20 of the nuts 18 effectively maintain the screws in parallelism with the side plate 5.

From the foregoing the merits and advantages of my present invention will be clearly apparent, while it is self-evident that I have provided a compact and effective adjuster means for pivoted elements. Hence I do not limit myself to the precise embodiment illustrated and described, but include all such other adaptations thereof as the scope of the following claims permit, and the prior art allows.

Having thus described my invention, what I claim is:—

1. Adjustment means for pivotal elements comprising a bearing member having an integrally formed abutment loop at each side of the pivot axis, adjuster screws afforded free guidance in the loops and engaging the pivotal element, and a nut on each screw having an eccentric face engaging with the bearing member to prevent its rotation while maintaining the screw in parallelism to such member with the nut lockingly engaging the associated abutment.
2. Adjustment means for pivotal elements comprising a sheet metal bearing member having an integrally formed abutment loop at each side of the pivot axis, adjuster screws afforded free guidance in the abutment loops and engaging the pivotal element, and a lock nut on each screw engageable below the associated loop and having a flat side in close proximity to its threaded bore, said flat side engaging the bearing member to prevent rotation of the nut while maintaining the screw in axial parallelism therewith.

In testimony whereof, I have hereunto signed my name at Philadelphia, Pennsylvania, this 14th day of Nov., 1929.

HERMANN M. HESSENBRUCH.
